BLOCK FORMING APPARATUS

George A. Vesper, Los Angeles, Calif.

Application December 4, 1947, Serial No. 789,706

3 Claims. (Cl. 25—84)

This invention relates to a machine for forming blocks and the like from comminuted fluent material; more particularly it relates to a machine for forming blocks, tile and the like from a fluent cementitious aggregate.

It is an object of this invention to provide an improved machine for this purpose.

It is another object of this invention to provide a machine capable of producing uniform and accurately shaped blocks.

It is another object of this invention to provide a machine utilizing pressure for compacting the blocks, having novel means for applying the pressure to the molded material.

It is another object of this invention to provide such a machine having novel means for altering the amount of compaction applied.

It is another object of this invention to provide a block forming machine having novel means for removing the blocks after the forming operation.

It is another object of this invention to provide a concrete block forming machine having novel means for removing the blocks from the mold.

It is another object of this invention to provide a concrete block forming machine employing a stationary mold so arranged as to be readily loaded and unloaded.

This invention possesses many other advantages and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

In the accompanying drawings:

Figure 1 is a side elevation partly in section, of a machine incorporating the features of the invention;

Figure 2 is a transverse section on an enlarged scale, taken substantially as indicated by line 2—2 of Figure 1;

Figure 3 is a view similar to Figure 2, but showing the parts in a different operating position;

Figure 4 is a fragmentary cross section showing the mold cover and operating mechanism therefor, taken substantially as indicated by line 4—4 of Figure 3;

2

Figure 5 is a fragmentary longitudinal section showing the mold cover and the mold, taken substantially as indicated by lines 5—5 of Figure 3;

Figures 6 and 7 are transverse sections, taken substantially as indicated by the correspondingly numbered lines on Figure 1;

Figure 8 is a schematic view showing the hydraulic operating means for the machine;

Figures 8-a, 8-b and 8-c are fragmentary views showing portions of the hydraulic system of Figure 8, under different operating conditions; and

Figure 9 is an isometric view of a finished block.

The machine comprises a stationary horizontal mold M with a movable bottom member B arranged to traverse substantially the entire depth of the mold, and a top closure member or head C movable between a position closing the mold and a position in which the top of the mold is open and substantially unobstructed. In operation, the bottom member B is retracted to an initial or lower position at a predetermined depth below the top of the mold, and the mold M is filled with the cementitious aggregate or other material to be formed. The head C is then moved to closed position, being so arranged as to extend into the mold and initially compress the material.

The means for moving the head exerts a large force on the head as it approaches closed position, and when the closure or head is in closed position, is capable of resisting a large force urging the head to open. The bottom member B is then urged upwardly to a definite position in the mold compressing the material against the head, and forming a block or blocks of a predetermined thickness.

After the bottom member B has completed the compression of the block, the head C is returned to open position; the bottom member then moving upwardly to force the blocks out of the mold and supporting them for removal by any suitable means.

Means are provided for altering the amount of compaction to which the aggregate is subjected. For this purpose, the initial or lower position of the bottom member B is made vertically adjustable. Since the mold M is always filled level with its top, the initial position of the bottom member B determines the amount of aggregate in the mold. Thus, since the bottom B is always moved to the same distance below the head C at the completion of its compressive stroke to form a

block of standard thickness or depth, the density of the block depends upon the amount of material in the mold. Means are also provided for adjusting the spacing between the head C and the bottom member B at the completion of the compressive stroke, so as to form blocks of a different thickness as required.

It is to be understood that the adjustment of the initial position of the bottom member B is to be made with due regard to the characteristics of the aggregate or material to insure the desired amount of compression upon compaction to the predetermined thickness.

Referring in detail to the machine, the mold M as shown in Figures 2, 4 and 5 comprises a rectangular space 5 with vertical side walls 6, 7, 8 and 9 formed in any convenient manner, for example, by structural iron members 10, 11, 12 and 13 of channel shaped cross-section of suitable depth. These members 10, 11, 12 and 13 are appropriately joined as by welding their adjacent corners, and are supported by the frame F of the machine. The side walls 6, 7, 8 and 9 may be provided with liners or protective plates 6-a, 7-a, 8-a and 9-a respectively.

The mold M may be divided by appropriate cross walls to form blocks of a desired size, suitable cores being provided to form hollow blocks. By way of example, the mold space 5 is shown as divided into three mold spaces M-1, to form three rectangular blocks D, one of which is shown in Figure 9. For this purpose, a pair of transverse walls 15 and 16 suitably secured to the side members 7 and 9 are provided and a pair of cylindrical cores 17 and 18 are supported in each of the spaces M-1, by a plate 19 extending between the bottoms of the members 7 and 9. These mold elements may be secured in any appropriate manner, as by bolts and screws, or welding (not shown).

The mold cover or closure head C comprises a backing plate 20 with a plurality of members 21 secured thereon, said members each having an external configuration and core openings 21-a such that the members 21 are capable of entering respectively the mold spaces M-1 (see Figures 3 and 5). Pairs of arms 22 and 23 are secured to the outer side of the backing plate 20 respectively near the opposite ends thereof and extend to the rear, engaging hinge pins 24 carried by ears 25 secured to the frame F at the back of the mold M.

A pair of links 26 and 27 is pivotally secured to the forward end of each pair of arms 22 and 23 as by pins 28, the other ends of each pair of links 26 and 27 being pivotally joined by a common pin member 29 to an upwardly directed arm 30, swingably supported by pins 31 suitably secured to a longitudinally extending frame member 32.

Each pair of links 26 and 27 together with the associated arm 30 forms a toggle structure T for swinging the cover C between open and closed positions. When the cover is in open position (Figure 2) the top of the mold is entirely clear and unobstructed. When the cover is in closed position the links 26-27 and arm 30 are aligned (Figure 3), so as to withstand a very great force urging the cover upwardly; also a very large force is exerted by the cover as it approaches closed position.

The means for operating the toggles T comprises a hydraulic cylinder 33 pivotally secured at its lower end to a longitudinally extending member 34 of the frame F, and having a piston 35 connected by a piston rod 35-a to the pin member 29. Admission and discharge of fluid to and from the opposite ends of the cylinder 33

is controlled by valves 36 and 37, as will be more fully described hereinafter. Opening movement of the closure C is limited by the engagement of the toggles T with a bar 38 provided on the frame F.

The movable bottom member B comprises a plurality of plates 40 respectively accommodated in the mold spaces M-1 and apertured for the cores 17 and 18, appropriate clearances being provided to permit free movement of the plates. A pallet member 42 of plate metal of suitable thickness rests on each of the plates 40, and is arranged to fit the mold space M-1 quite closely, so as to form the bottom closure therefor.

The plates 40 are supported in spaced relation above a vertically movable pressure head 43, by a plurality of posts 44, suitably secured respectively to the plates 40 adjacent the corners thereof. The posts 44 extend through clearance openings provided in the head 43 and are threaded for the reception of nuts 45 and 46 respectively engaging the upper and lower surfaces of the head 43. By adjusting the nuts 45 and 46, the spacing of the plates 40 above the head 43 may be varied, as will be more fully pointed out hereinafter. The head 43 is supported for vertical movement in two steps by a dual cylinder hydraulic mechanism 50.

Referring particularly to Figure 3, the mechanism 50 is shown as comprising a main or first cylinder 51 of large diameter having upper and lower heads 52 and 53 respectively, the upper head 52 having oppositely directed extensions 52-a and 52-b by the aid of which the mechanism 50 is mounted on parallel spaced beams 54 of the frame F. A piston 55 is provided in the cylinder 51, having a tubular member 56 secured thereto which forms a piston rod extending upwardly through a boss 52-c on the head 52, suitable packing means being provided to seal about the member 56. The upper end of the member 56 is provided with a closure or head 57, the lower end of member 56 opening into the cylinder 51 below the piston 55. The member 56 forms a supplemental or second cylinder, and has a piston 58 therein secured to the lower end of a rod 59, which extends upwardly through the closure 57 and has the head 43 secured to the upper end thereof.

The head 57 of the supplemental cylinder 58 is provided with annular extensions or flanges which provide an upper surface 57-a for supporting the pressure head 43 when the piston 58 is in its lower or retracted position in cylinder 56 (see Figure 3), and a lower surface 57-b for supporting the piston 55 in its adjusted lower or initial position.

It will be clear that the position of the plates 40 and pallets 42 in the mold spaces M-1 below the top of the mold when the pressure head 43 is supported on the surface 57-a, will depend upon the height of such initial position. Thus, by adjusting this position, the effective volume of the mold spaces M-1 may be altered which will vary the amount of aggregate provided for each block, since the mold is always filled flush with the top.

Accordingly, adjustable means are provided for limiting the downward movement of the piston 55, etc., and to support the piston 55 in its initial position. The boss 52-c serves by engagement with the surface 57-b to support the head 43, and the bottom member B in their lowest adjusted position, as shown diagrammatically in Figure 8.

To support the head 43 and bottom member B at higher positions, one or more spacer rings 60 are placed on the boss 52-c encircling the member 56, three such rings 60 being shown by way of example in Figures 2, 3 and 5. To permit ready placement and removal, the rings 60 are made in halves, and to maintain them in stacked relation they are provided on their opposite edges with tongues 60-a and recesses 60-b adapted for interengagement.

Upward travel of the head 43 and the bottom member B is always terminated at the same point, by engagement of the piston 55 with the top head 52 (Figures 3 and 5). Since the cover members 21 always occupy the same position when closed, the material in the mold spaces M-1 will always be compressed to a predetermined thickness. Accordingly, adjustment of the initial position of the member B varying the amount of aggregate in the mold spaces M-1 will result in altering the amount of compaction of the aggregate in the finished block.

Adjustment of the rods 44 will alter the position of the bottom member B at the completion of the upstroke, and thus serve to vary the thickness of the finished block D. These rods 44 also enable individual adjustment of the plates 48, as may be required.

Fluid pressure in the cylinder 51 below the piston 55 also acts on the supplemental piston 58 urging it upwardly. However, upward movement of the piston 58 with respect to piston 55 is prevented by a body of liquid confined in cylinder 56 between piston 58 and the head 57.

Means are provided for releasing this liquid after the upward stroke of the piston 55 has been completed and the mold cover C swung to open position. Thus, the fluid pressure in the cylinder 51 becomes effective to move piston 58 to the upper limit of its stroke in the cylinder 56, moving the head 43 and the bottom B further upwardly so that the pallets 42 with the blocks D thereon are supported above the mold M (see Figures 1 and 2). From this position the pallets 42 and blocks D may be readily removed and transported as required for further processing of the blocks.

To facilitate operation of the machine, it is desirable to provide means for rapidly filling the mold M and for removing the formed blocks D after ejection therefrom. For this purpose, the frame F which supports the mold and pressing apparatus may have oppositely directed longitudinal extensions F-1 and F-2, as shown in Figure 1.

The frame extension F-1 has a horizontal plate 70 (Figures 1, 5 and 6), the upper surface of which forms a continuation of the top surface of the mold M. A shorter plate 71, supported on the frame F as by brackets 72 forms a similar continuation in the opposite direction. A pair of structural members 73 and 74 supported in parallel spaced relation respectively above the opposite edges of the plate 70 serve to rotatably mount rollers 75.

A rectangular box like member 76 having front and back walls 76-a and 76-b, side walls 76-c and open top and bottom is supported by the rollers 75 so that its lower edges are spaced above plate 76 by a suitable clearance, means being provided to cause the member 76 to traverse the mold M to a position such as indicated by the broken lines. The loading member 76 has a rear extension 78 with a horizontal plate 79 the full

width of the member 76. Spaced parallel rails 80 and 81 are provided along each side wall 76-c and along the rear portion 78 and cooperate with the rollers 75 to support the member 76. A hopper 82 or the like defining a space to receive the aggregate of which the blocks are to be formed is provided on the frame F-1 closely spaced above the member 76, and opens thereinto.

The arrangement is such that aggregate A in the hopper 82 substantially fills the space defined by the loading member 76, being supported on the plate 70. Upon movement of the member 76 to the right across the mold M, the material fills the mold spaces M-1, plate 79 serving to support the material in the space 82 at this time. The member 76 is then moved back across the mold M removing the excess material from the mold and receiving additional aggregate from the space 82.

A hydraulic cylinder and piston arrangement 84 controlled by a valve 85 is provided for moving the member 76. Thus, as shown in Figure 1, the cylinder 84-a is secured to the frame extension F-1 and has a conventional piston (not shown) attached to the back wall 76-b of the member 76 by a piston rod 84-b engaging a pin and clevis 84-c.

The frame extension F-2 comprises a pair of spaced horizontal members 90 (Figure 7), each having rail forming means 91 thereon. An off bearer 92 is provided for removing the blocks D after ejection from the mold M and comprises a rectangular frame 93 with rollers 94 on opposite sides thereof supporting the frame 93 for longitudinal movement along the rails 91. A pair of elongated elements 95 and 96 depend from each side of the frame 93 and are joined at their lower ends by a horizontal supporting member 97, each of which has an inwardly directed flange 97-a.

The arrangement is such that when the mold bottom member B is in its uppermost position the pallets 42 are spaced sufficiently above the top of the mold M to accommodate the flanges 97-a beneath them, the elements 95 and 96 being of such length that suitable clearance is provided between the members 97 and the top of the mold. Further, the pallets 42 overhang the edges of the plates 40 by a short distance, all as shown in Figure 2.

In using the off bearer 92, the blocks D are positioned above the mold, as previously described; the off bearer 92 is then moved to position the flanges 97-a beneath the pallets 42. The hydraulic means 51 is then operated to lower plates 40, allowing the pallets 42 to be supported by the flanges 97-a of the off bearer 92, and the off-bearer moved to the right (Figure 1), removing the blocks from above the mold M. The blocks D may then be removed from the off-bearer 92 for further handling by appropriate means (not shown).

The machine together with the hydraulic operating means and controls therefor are shown schematically in Figures 8, 8-a, 8-b and 8-c. Therein a pump of any suitable type indicated by the numeral 100, is arranged to deliver suitable liquid from a sump or reservoir 101 continuously to a conduit 102 while the machine is in use. A conventional relief valve 103 is provided to return the liquid directly to the sump 101 in case pressure in the system reaches an excessive amount due to failure or jamming of the parts.

The control valves 36, 37 and 85 may be four way valves of conventional type, and are shown diagrammatically in Figure 8. Thus, referring to valve 36, it is shown as comprising a circular housing 36-a having oppositely disposed ports 104 and 105, and a fluid pressure inlet and outlet 106 and 107 respectively spaced 90° from the ports 104 and 105. A closure member 36-b is rotatable in fluid tight relation in the housing 36-a and has a pair of through passages 108 and 109 opening respectively at points spaced 90° about the member 36-b.

In Figure 8 the member 36-b is shown in neutral position, closing ports 104 and 105 as well as the inlet and outlet 106 and 107. Rotation of member 36-b clockwise through an angle of 45° to the position shown in Figure 8-a, establishes communication between port 104 and the outlet 107 via passage 108, and between port 105 and the inlet 106 via passage 109. Rotation of member 36-b from the position of Figure 8, counterclockwise through an angle of 45° to the position of Figure 8-c establishes communication between port 105 and the outlet 107 via passage 109 and between port 104 and the inlet 106 via passage 108. Valves 37 and 85 are substantially identical with valve 36, except that the rotatable member in each valve 37, 85, as shown for example in the member 37-b of valve 37, has a bypass port 110 for connecting the inlet 111 with the outlet 112 when the member 37-b is in neutral position.

A valve capable of performing the above function but employing a reciprocable closure instead of an angularly movable closure, is commercially available from Vickers Ltd., being known as a four-way spool valve. In Figures 2, 3 and 4, the valves 36 and 37 are shown as of this type, the piping for conducting fluid to and from the valves being omitted for the sake of clarity.

A reciprocable rod 115 is provided for operating the closure of valve 37, being pivoted to the lower end of a lever 116 pivotally mounted at 117 on the main frame F (see particularly Figure 2). An operating arm 118 is secured to the lever 116, and by movement upwardly or downwardly from the position shown, serves to operate the valve 37 to perform functions analogous to that described in connection with valve 36 and Figure 8.

The valves 36 and 85 are similarly provided with operating arms 119 and 120 respectively, and it is preferred that the closure in each valve 36, 37 and 85 be spring biased to neutral position.

Referring to Figure 8, the closures of valves 36, 37 and 85 are shown in their neutral positions, thus blocking the ports communicating with the ends of cylinders 33, 51, 56 and 84 respectively controlled by the valves, trapping the liquid and locking the pistons in the cylinders against movement, the member 76 being in retracted position, the mold cover C being open and the pressure head 43 being in its adjusted lower or initial position. Liquid from the pump 100 freely by-passes valve 85 to conduit 121, through by-pass 110 in valve 37 and via conduit 122 to the sump 101. Thus, under these conditions the only load in the pump is a small friction head.

The first step in operating the machine requires the filling of the mold M. For this purpose, the closure of valve 85 is operated (turned clockwise through 45° from the position shown in Figure 8) to connect the pump 100, via conduits 102 and 123 to the left hand end of the

cylinder 84 and closing the by-pass through the valve 85. Thus, the loading member 76 is caused to traverse the mold M, the liquid in the right hand end of the cylinder 84 discharging through conduits 124 and 121 which were also connected by the clockwise movement of the valve closure, valve 37 and conduit 122 to the sump 101.

Upon completion of the movement to the right of the loading member 76, the closure of valve 85 is operated (turned counterclockwise through 45° from the position shown in Figure 8) to connect the right hand end of the cylinder 84 to pump 100 via conduit 124 and the left hand thereof to discharge via conduits 123, 121, valve 37 and conduit 122. This causes the member 76 to return to its initial position, whereupon the valve 85 is returned to neutral connecting conduit 121 with the pump 100.

After the mold M has been filled, the cover C must be moved to closed position. An important safety feature of this control mechanism is that valves 36 and 37 must be operated simultaneously to close the mold cover. Thus, accidental operation of one valve will not cause the cover C to close with accompanying possibility of injury to the operator. Further, the operator must have a hand on each valve, obviating the possibility of closing the cover while having one hand between the cover and the mold, such as would exist if a single valve controlled the cover movement.

The ports 104 and 105 previously described in connection with the valve 36 are connected respectively with the upper and lower ends of the cover or closure head operating cylinder 33 by conduits 125 and 126. The outlet 107 is connected to conduit 122 and thence to the sump 101 by conduit 127, and the inlet 106 is connected by conduit 128 to a diverter valve 129, adapted to supply liquid under pressure to conduit 128, as will be pointed out presently.

The valve 37 includes the valve body 37-a with oppositely disposed ports 135 and 136, spaced 90° from the inlet 111 and the outlet 112. Port 136 is connected with the lower end of cylinder 51 by conduit 137 and thence with the lower end of cylinder 56 which opens through the bottom of piston 55. The port 135 is connected with the upper end of cylinder 51 by conduit 138. The upper end of cylinder 56 is adapted to communicate with conduit 138 and thence with port 135 by a connection including a check valve 139 and a relief valve 140. The arrangement is such that when piston 58 is urged upwardly in the cylinder 56 with sufficient force, the relief valve 140 will permit liquid to be discharged allowing piston 58 to move upwardly. Check valve 139 permits liquid to be returned for urging piston 58 downwardly in cylinder 56.

The diverter valve 129 comprises a body having a horizontal chamber 141 in which is a freely movable valve member 142, which may conveniently be a steel ball. Horizontally directed inlet ports 143 and 144 are provided at opposite ends of the chamber 141, and an outlet port 145 extends transversely from the mid-point of the chamber 141. The inlet 106 of valve 36 is connected with port 145 by the conduit 128, the inlet ports 143 and 144 being connected respectively with conduits 137 and 138 by conduits 147 and 148.

To cause the cover C to move to closed position, the valve closure 36-b is turned 45° clockwise and valve closure 37-b is turned 45° counterclockwise from the positions shown in Figure 8,

to the positions shown in Figure 8-a. This closes the by-pass port 110 and directs liquid under pressure from the conduit 121 to conduit 138 and the upper ends of cylinders 51 and 56. However, since the pistons 55 and 58 are already at their initial adjusted lower positions from the preceding operation of the press, these pistons do not move. Liquid under pressure also passes from the conduit 138 via conduit 148 to the diverter valve 129 urging the closure 142 to close port 143 and opening port 144 so that liquid may enter chamber 141 and pass via outlet 145, conduit 128, valve 36 and conduit 126 to the lower end of cylinder 33. The upper end of cylinder 33 is connected via conduit 125, valve 36, and conduit 127 to the discharge conduit 122; the lower end of cylinders 51 and 58 are connected with the discharge conduit 122 via conduit 137 and valve 37.

The pressure in the lower end of the cylinder 33 urges the piston 35 therein upwardly until the links 26-27, 30 of the toggles T are aligned and the cover C is in closed position, further movement of the piston 35 being prevented by the piston contacting the upper end of the cylinder 33 (see Figure 3). The valve 36 may be allowed to return to neutral position as soon as the cover is closed, since in such position liquid is trapped in both ends of the cylinder 33, preventing return movement of the piston 35, and release of the toggles T.

After the cover C has been closed the valve 37 is operated to reverse the pressure conditions in the cylinders 51 and 56 by connecting conduit 137 with the pressure conduit 121, and conduit 138 with the discharge conduit 122, as shown in Figure 8-b. Under these conditions liquid under pressure from conduit 137 acts in chamber 141 through conduit 147 and port 143 to cause the valve member 142 to close port 144. This causes the pistons 55 and 58 to move upwardly together, movement of the piston 58 in cylinder 56 being prevented by liquid trapped therein by the check valve 139 and relief valve 140. This movement continues until piston 55 contacts the upper cylinder head 52 and constitutes the forming or pressing movement, the accompanying movement of the mold bottom member B compressing the material in the mold M against the cover C. The toggles T, provided for holding the cover C closed, enable the cover to withstand a large force against its lower face, urging it to move to open position.

Upon completion of the upward stroke of piston 55, valve 36 is operated to reverse the pressure conditions in the cylinder 33 by connecting conduit 125 with the pressure inlet 106 and conduit 126 with the outlet 107, as shown in Figure 8-c, liquid under pressure passing from the conduit 137 via conduit 147, port 143, valve chamber 141, port 145, and conduit 128 to inlet 106. This liquid pressure acts in the upper end of cylinder 33 to cause piston 35 to "break" the toggles T and lift the cover C to open position. This frees the material in the mold M for ejection by a further or supplemental upward movement of the bottom member B, caused by upward movement of the piston 58 in cylinder 56. However, such movement is prevented by the liquid trapped in cylinder 59 above the piston 58. When the cover C is fully open, movement thereof is stopped by engagement of the toggles T with the bar 38 on the frame F. Pressure thereafter builds up until the upward force acting on the piston 58 is sufficient to cause the trapped liquid in the cylin-

der 56 to open the relief valve 140, whereupon this liquid discharges via conduit 138, valve 37 and conduit 122. This allows the piston 58 to move upwardly and cause the bottom member B to eject the formed material from the mold M.

To return the mold bottom B to its initial position the valve 37 is operated to reconnect conduit 138 with inlet 106, thus supplying liquid under pressure to the upper end of cylinder 51 and via check valve 139 to the upper end of cylinder 56. The lower ends of cylinders 51 and 56 being connected to the sump 101 via conduit 137, valve 37 and conduit 122, the piston 58 returns to cause the pressure head 43 to seat on surface 57-a, and piston 55 returns to its initial position, as determined by the adjusting rings 60 which engage the surface 57-b.

Since after completion of a forming operation, the pistons 55 and 58 must always be returned to their initial lower positions before filling the mold M, it is possible to operate the machine by operating valves 36 and 37 to cause the cover C to close to urge piston 55 and connected parts upwardly.

Due to the fact that less force is required to close the cover C than to raise piston 55, head 43, mold bottom B and the material in the mold M, the cover will close before the piston 55 starts to move up. When the cover is in closed position, the toggle links 26-27 and arms 30 are aligned and the piston 35 in cylinder 48 is stopped by engagement with the upper head of the cylinder 33, as before described. This will cause pressure to build up in cylinder 51 so that the mold bottom B is urged upwardly to compress the material in the mold against the cover C, in the same manner as before.

It will be seen that operation of the valve 36 while valve 37 is in neutral position will not cause movement of the cover C, since under that condition no liquid pressure is present at the inlet 106. The valve 37 must be moved so that the by-pass port 110 is closed and pressure is admitted to either conduit 137 or 138 before closing movement of the cover C can occur in response to opening the valve 36. Since valves 36 and 37 are both spring biased to neutral position, both of the operator's hands are required for simultaneous operation of the valves.

It is to be understood that conventional means may be provided in connection with any of the hydraulic cylinders and pistons for retarding the piston near the end of its stroke, such means commonly comprising an arrangement whereby the piston at an appropriate point in its stroke reduces the effective area of an outlet port from the cylinder.

I claim:

1. In block forming apparatus: means forming a molding space having vertically extending side walls; a closure head for the upper end of said space, movable between open and closed positions; means for operating said closure head to open and closed positions; a bottom closure member for said space, movable upwardly therethrough; means for moving said member upwardly within the mold to a predetermined point when said head is in closed position, and thereafter, when the head is in open position, for moving said member to project from said space, comprising a first hydraulic cylinder and piston, means whereby said piston supports said member; a second hydraulic cylinder and piston, said second cylinder being connected to move with the first piston, the second piston being con-

11

nected to move with said member; the spaces in said cylinders below the pistons being in free communication; means for supplying fluid pressure to raise the first piston; means forming a fluid lock preventing relative movement between said second cylinder and piston, whereby said pistons move together; and means for releasing the locking fluid to cause the second piston to move in response to said fluid pressure.

2. In block forming apparatus: means forming a molding space having vertically extending sides; means forming a closure, movable between a position closing the upper end of said space and an open position; means forming a bottom closure member for said space, movable upwardly therethrough; support means for said member including a cylinder and piston structure; spacer means cooperating with said structure to support said member at an adjusted height in said space to alter the capacity thereof; said structure being operable to move said member upwardly from said position to compact material in said space; stop forming means to limit upward movement of said member by said structure to a predetermined distance below said closure, independent of said adjusted height; and means for thereafter moving said member to extend above the top of said space when said head is in open position, including a second cylinder and piston structure.

3. In block forming apparatus: means forming a molding space having vertically extending side walls; a closure head for the upper end of said space swingably mounted exteriorly along the rear side of the mold for movement between open and closed positions; means for operating said closure head to open and closed positions, comprising a pair of links pivotally joined at their adjacent ends to form an upwardly extending toggle structure, pivoted at its lower end to said head adjacent the forward side of the mold; means forming a frame supporting said mold forming means and including a plurality of ver-

12

tically spaced horizontal members rearwardly of the mold; means pivotally supporting the upper end of said toggle structure on the uppermost of said members; means for moving said links to operate said head interposed between another of said members and the pivotal connection between the links; the other member being adapted to engage said toggle structure and limit its movement in head opening direction; and a bottom closure for said space, movable upwardly to compact material therein against said head.

GEORGE A. VESPER.
